PAGE 3

FIG. 7.

FIG. 9.

FIG. 8.

FIG. 10.

FIG. 12.

FIG. 11.

In the drawing:

FIG. 1 is a front perspective view of a new design for a motion picture projector or the like with the cover removed;

FIG. 2 is a front elevation thereof;

FIG. 3 is one end view thereof;

FIG. 4 is a top plan view thereof;

FIG. 5 is a rear elevation thereof;

FIG. 6 is another end view thereof;

FIG. 7 is a front perspective view of the design for a motion picture projector or the like as shown in FIG. 1, however, with the cover in place;

FIG. 8 is a front elevation of the latter;

FIG. 9 is one end view thereof;

FIG. 10 is a top plan view thereof;

FIG. 11 is a rear elevation thereof; and

FIG. 12 is another end view thereof.

I claim:

The ornamental design for a motion picture projector, as shown.
